UNITED STATES PATENT OFFICE.

AUGUST E. ROEVER, OF BROOKLYN, NEW YORK.

CLOTHES-WASHING MACHINE.

1,396,465.

Specification of Letters Patent. Patented Nov. 8, 1921.

Application filed June 7, 1920. Serial No. 386,990.

To all whom it may concern:

Be it known that I, AUGUST E. ROEVER, a subject of Germany, having applied for naturalization as a citizen of the United States, and received my first papers, and still intending to become such citizen, residing at Brooklyn, in the county of Kings and State of New York, have invented certain new and useful Improvements in Clothes-Washing Machines, of which the following is a specification.

This invention relates to clothes washing machines, the object of the invention being to provide an improved machine of the class described in which the articles to be washed will be subjected to the combined action of water, air pressure and vacuum, while the receptacle in which they are contained will also be rotated, whereby a very effective rubbing cleansing of the articles being washed is obtained.

A further object of the invention is the provision of a simple and readily operative mechanism by means of which the foregoing results may be obtained and which will be durable in use and can be inexpensively manufactured, and also may be so made as to be portable, if desired.

In the drawings accompanying and forming part of this specification, Figure 1 is a cross sectional view of this improvement, the removable cover being shown in dotted lines and Fig. 2 is a top view of the improvement with the cover removed.

Similar characters of reference indicate corresponding parts in the two figures of the drawing.

In the preferred form thereof, herein shown, this improved washing machine comprises a suitable receptacle 2, preferably having at one side thereof a support or platform 3 on which may be mounted a suitable motor 4, connected with a fan 5 located in a suitable housing or casing 6, shown herein as formed from a part of the main casing wall. The shaft 7 of the motor extends through the housing, and this shaft carries the fan, the shaft continuing to and is supported by the opposite wall of the receptacle 2. Preferably adjacent to the fan the shaft carries a spur gear 8 adapted to mesh with an annular gear 9 secured to the exterior of a rotary drum 10 perforated along its sides and bottom as at 11. The bottom only, or the bottom and a portion of the side only may be perforated, if desired. The under-

side of this annular gear forms a track to run on suitable rollers 12 carried by projections 13 secured around the inside of the receptacle 2. From this it will be observed that on the rotation of the spur gear, the drum will be rotated in a horizontal path relative to its vertical axis. The drum, as hereinbefore stated, is perforated, or may be formed of foraminous material into which the clothes to be washed are placed.

Communicating with the fan housing or chamber, 6, is a pair of tubes or pipes 14, the horizontal portions 15 of which extend along under the wire mesh drum and are perforated for the passage of air to and through the drum and the water contained therein, and in the receptacle 2 whereby as the fan rotates the air is forced through the water and into the clothes and through the same to effect and facilitate the washing thereof.

The shaft carrying the fan and the spur gear, and which shaft extends across the top of the receptacle 2 is provided with a pair of cranks 15' and 16 angularly located relatively to each other and to which are connected adjustable plunger rods 17, each carrying a plunger in the form of a cup, one as 18 being shown as conical and the other 19 as semi-spherical merely to show the different styles which may be used.

It will be observed that in the operation of this machine in which, if desired, any preferred number of plungers may be used, as one plunger compresses and forces the dirt and water out of the clothes, the other sucks the dirt and water therefrom. At the same time the air which is compressed by one plunger is forced thereby and by the simultaneous action of the fan through the water and the clothes adjacent to a companion plunger, thereby to expand and open up the clothes. Thus the clothes are washed by the combined action of water, pressure and vacuum in connection with the forcing of air therethrough, so that a very effective and thorough cleansing of the clothes is obtained by a very simple and durable apparatus. During this operation the drum is rotated, so that the clothes being washed will be rotated with the drum.

The drum furthermore, during its rotation, is effective to rub the clothes, due to the fact that owing to the pressure of the plungers alternately upon the clothes, the latter therefore will be alternately held from ro-

tation and then rotated upon release of the plungers. Thus during the operation of the plungers upon the clothes the drum will rotate relatively thereto thereby insuring an efficient rubbing action to assist in removing the dirt from the clothes.

From the foregoing it will be observed that the clothes are effectively washed by the combined action of water, air pressure, 10 vacuum and a rubbing action.

It will also be readily observed that inasmuch as the fan is operated simultaneously with the vacuum and suction plungers, the air is forced by the fan into and through 15 the clothes conjunctively with the simultaneous suction or drawing of the air and water through the clothes by the vacuum plungers. The clothes in this manner are more readily and efficaciously cleansed.

20 The casing 2 is provided with a removable cover 20 and the entire structure may be made in the form of a boiler, if desired.

It will be understood, of course, that the various details may be more or less changed 25 without departing from the spirit or scope of this improvement as defined in the appended claims, and that the term "foraminous" as used therein is intended to cover any form of perforated or open mesh drum 30 which it may be desired to use.

I claim as my invention:

1. In a washing machine, the combination of a receptacle, a crank shaft supported thereby, a foraminous drum supported 35 within said receptacle, means carried by the shaft for rotating said drum in a horizontal path, one or more plungers carried by said shaft, means for rotating said shaft, and a motor driven rotary fan on said shaft for 40 forcing air into said drum.

2. In a washing machine, the combination of a receptacle, a crank shaft supported thereby, a foraminous drum supported within said receptacle, means carried by the 45 shaft for rotating said drum in a horizontal path, one or more plungers carried by said shaft, a fan chamber supporting said shaft at one side of said receptacle, a fan therein, one or more perforated pipes communicating 50 with said fan chamber and opening adjacent to said drum, and a motor for driving said crank shaft and fan.

3. In a machine for washing clothes, the combination of a receptacle, a crank shaft 55 supported thereby, a foraminous drum solely supported at its top within said receptacle for horizontal movement, an annular gear carried by said drum, a gear carried by said shaft for rotating said drum, an adjustable 60 plunger rod carried by said shaft, a vacuum cup carried thereby, and motor driven means for rotating said shaft.

4. In a washing machine, the combination of a receptacle, a crank shaft supported 65 thereby, a foraminous drum located within

said receptacle for horizontal movement, means located exteriorly of said drum for rotating it and comprising an annular gear carried by said drum, a gear carried by said shaft, a plunger rod carried by 70 said shaft, a vacuum cup plunger carried thereby, means for rotating said shaft, a fan located on said shaft, and a perforated pipe in communication with said fan and extending along the bottom of said 75 foraminous drum.

5. In a washing machine, the combination of a receptacle having a fan chamber at one side thereof, a crank shaft extending through said chamber and along the top 80 of said receptacle, a fan carried by said shaft, a plurality of plungers carried by said crank shaft, a foraminous drum located within said receptacle, an annular gear carried by said drum, a gear on said crank shaft 85 and in mesh with said annular gear, one or more pipes connected with said fan chamber and having perforations along the bottom of said foraminous drum, and means for operating said crank shaft.

6. In a washing machine the combination of a receptacle, a foraminous drum, an annular drum carried by said drum at the top thereof, means carried by the receptacle for supporting said gear and thereby suspending 95 the drum in the receptacle, a crank shaft extending across the top of said drum, a plurality of plungers carried by said shaft and in mesh with said annular gear, a rotary fan pump operated by said shaft for 100 forcing air into said drum, and motor driven means connected with said shaft for rotating it and thereby the drum.

7. In a washing machine, the combination of a receptacle having a fan chamber at one 105 side thereof, a crank shaft extending through said chamber and along the top of said receptacle, a fan operated by said shaft, a plurality of vacuum cup plungers carried by said crank shaft, a foraminous drum supported within said receptacle independently of the bottom thereof, an annular gear carried by said drum, a gear on said crank shaft and in mesh with said annular gear, one or more pipes connected with said 110 fan chamber and having perforations along the bottom of said foraminous drum, a motor 115 for operating said crank shaft, and means carried by said receptacle for supporting said motor adjacent to the top thereof.

8. In a washing machine, the combination of a receptacle having a series of projections carrying rolls, a foraminous drum located within said receptacle and provided with an annular gear supported on said rolls, a crank 120 shaft supported along the top of said receptacle and carrying a gear in mesh with said annular gear for rotating the drum in a horizontal plane, a plurality of cup-shaped plunger cups secured to said crank shaft, 125

- a fan chamber carried by said receptacle, a fan located therein and carried by said crank shaft, a plurality of perforated pipes located between the receptacle and the drum 5 and having perforations along the bottom of said drum and in communication with said fan chamber, and a motor carried by said receptacle for rotating the crank shaft, thereby to simultaneously operate the fan, 10 rotate the drum and reciprocate the plungers.
9. In a machine for washing clothes, the combination of means comprising a vacuum plunger operative to subject the clothes to a vacuum, means effective to force air into and 15 through the clothes, and means for operating both of said means simultaneously.
10. In a machine for washing clothes, the combination of means comprising a suction plunger operative to subject the clothes to 20 suction, means effective to force air into and through the clothes, means for rotating the clothes, and means for operating all of said means simultaneously.
11. In a machine for washing clothes, the combination of means comprising a plurality of vacuum plungers operative to subject the clothes to pressure and vacuum, means effective to force air into and through 25 the clothes, and means for operating both of said means simultaneously.
12. In a machine for washing clothes, the
- combination of means comprising a plurality of vacuum plungers operative to subject the clothes to pressure and vacuum, means effective to force air into and through the clothes, means for rotating the clothes, and motor driven means for operating all of said means simultaneously.
13. In a clothes washing machine, the combination of suction plunger devices adapted 40 to subject the clothes to suction, means for continuously forcing air into and through the clothes, means comprising a rotatable container effective during the operation of said plunger devices for rotating and rubbing the clothes, and means for operating all of said means simultaneously.
14. In a machine for washing clothes, the combination of means comprising a vacuum plunger adapted to subject the clothes to a 45 vacuum, means comprising a fan pump for forcing air into and through the clothes, means comprising a rotatable container adapted to rotate the clothes during the operation of said plunger devices, and power 50 driven means for operating all of said means simultaneously.

Signed at New York city, in the county and State of New York, this fourth day of June, 1920.

AUGUST E. ROEVER.
